UNITED STATES PATENT OFFICE.

JOHN DOYLE, OF NEW YORK, N. Y.

LOCKING DEVICE FOR GAS-COCKS.

SPECIFICATION forming part of Letters Patent No. 576,958, dated February 9, 1897.

Application filed April 18, 1896. Serial No. 588,148. (No model.)

To all whom it may concern:

Be it known that I, JOHN DOYLE, a citizen of the United States, residing in the city, county, and State of New York, have invented 5 a new and useful Improvement in Locking Devices for Gas-Cocks, of which the following is a specification.

My invention relates generically to devices for locking cocks and valves and also for limiting their operation; and it relates specifically to gas-supply cocks and to means for locking them when shut off and for limiting the extent of their opening.

Among the particular objects of my invention are to provide gas-supply cocks with a locking device which is entirely inclosed, so that it cannot be broken, tampered with, or unlocked excepting by the proper key, and which is of simple and strong construction, 20 and also with simple and effective means for adjusting and limiting the extent of opening of the cock, so that no more than a predetermined supply of pressure or gas can pass through the cock.

In order that my invention may be clearly ascertained, I shall first describe in detail the mode in which I carry the invention into practice, and then particularly point out the invention in the claims.

Reference is to be had to the accompanying drawings, forming part of this specification, in which like parts are designated by the same letters in all the figures.

Figure 1 is a sectional view of a gas-cock embodying my invention on the line 1 1, Fig. 2. Fig. 2 is a sectional view of the same on the line 2 2, Fig. 1. Fig. 3 is a longitudinal sectional view of the cock-casing.

A designates the casing of a gas-cock; B, the core; C, the core-washer, and D the core-retaining nut, the core B being shown in Fig. 1 closed to completely shut off the cock.

I prefer to construct the core B in two sections, the section B' constituting the body of the core and having the transverse gas-passage C to register, when opened, with the gas-passages in the casing, and the section B² united to the section B' and formed with the usual flat stem E for turning the cock.

The top of the core-section B' is by preference closed by a solid head D to prevent the gas from passing into the outer part of

the core, and the core-section B² is chambered at G to fit flush over the head D of section B' and is fastened thereto by screws F within 55 the casing A, so as to form the complete core.

In the chamber G of the core-section B² and on the head D of the core-section B', I prefer to mount a sliding bolt H, having in this instance two ordinary locking-tumblers I, which 60 bolt is adapted to work through a lateral slot J in core-section B², and, when the cock is shut off, into a corresponding bolt-hole K, which I form in the interior of the casing A, so that the cock-core will then be securely 65 locked against turning and the cock against opening. At the same time it will be impossible, owing to said locked bolt, to withdraw the core from the casing and thus reach either the bolt or the incased screws F, which secure 70 the core-section B² to the core-section B', so that no one, unless armed with the proper key, can open or disarrange the cock so as to allow the gas to pass therethrough.

I provide for locking and unlocking the 75 cock-bolt H by means of an appropriate key L, inserted in a key-slot M, which I form axially through the core-stem E, so as to lead to the lock-chamber G and to the bolt H and tumblers I.

For adjusting and limiting the opening of the cock and thus the possible supply of gas therethrough I form a series of (in this case) three concentric slots O of varying lengths in the interior of the casing A, and in the core-section B² a corresponding series of sockets or holders P, in one of which holders a peg or stop Q is screwed when the core is withdrawn from the casing, so as to (when the core is in place) ride in one of the concentric slots O, 85 and thus limit the rotation of the core and opening of the cock, according to the length of the particular slot O selected, without in any way interfering with the complete closing of the cock. The cock can thus be set 90 to admit only a predetermined supply or pressure of gas or can be closed and locked, so as to absolutely prevent any gas from being admitted therethrough.

I claim as my invention—

1. The cock herein described as having its casing formed with a bolt-hole on its inside, and its core constructed of two sections, inclosing therebetween a locking-bolt, and

united by fastenings as screws, whose heads are covered and sealed by the casing, and locked by the bolt inside the casing.

2. The combination with the casing of a cock having a bolt-hole on its inside, of a cock-core constructed of two sections inclosing therebetween a chamber, fastenings uniting said sections and sealed by the casing and a locking-bolt working in said chamber through the wall of the outer section of the core into said bolt-hole, said outer section of the core being provided with a key-slot to admit a bolt-locking key.

3. The combination, with the casing of a cock having a series of concentric slots of varying lengths, of a cock-core having an adjustable stop to ride in either of said slots, and variably limit the opening of the cock.

4. The combination, with the casing of a cock having a bolt-hole and a series of slots of different lengths, of a cock-core having an

adjustable stop to ride in either of said slots, a bolt in the core, and means for operating the bolt by a key.

5. The combination, with the casing of a cock having a bolt-hole and a series of slots of different lengths, of a cock-core having an adjustable stop within the casing to ride in either of said slots, a bolt in the core and means for operating the bolt by a key. 25 30

6. The combination, with the casing of a cock having a series of slots of different lengths, of a cock-core having a series of stop-holders corresponding to the respective slots, and a stop to be held in one of said stop-holders. 35

In testimony whereof I have hereunto set my hand this 30th day of March, 1896.

JOHN DOYLE.

In presence of—

WILLIAM R. BAIRD,
CLARENCE L. BURGER.
